TENSION MEANS FOR WINDING MACHINES

Frederick Klein, Glen Rock, N. J., assignor to
Sipp-Eastwood Corporation, Paterson, N. J., a
corporation of New Jersey

Application May 15, 1936, Serial No. 79,844

3 Claims. (Cl. 242—150)

This invention relates to mechanism for tensioning yarn anterior to draft means therefor.

It is known to provide a yarn-support which may tilt and a pressure device coactive therewith to grip the yarn and normally urged (as by gravity) in a straight path extending through, and crossing the pivoting axis of, such support, the mechanism having yarn guiding means confining the yarn between said support and device. The present invention distinguishes from what is thus known principally in that there are means to guide the yarn which are offset from each other lengthwise of the pivoting axis of the support; this has the important advantage that the support on shifting may be adapted not of itself to cause bending, with friction and hence the intrusion of a tension factor other than that contemplated by the action of the pressure device. In the preferred form one of the yarn guiding means is arranged at the output side of the pressure device and has a yarn-contact surface extending transversely of said axis. Preferably, also, there is a plurality of the pressure devices and what confines them to the support may be the yarn guiding means, arranged as indicated.

In the example herein set forth yarn is being formed into a wound mass on a suitable rotated core, being anterior to the core subject to the tension means above generally outlined, and there is means, normally held bearing against said mass peripherally thereof and connected with the yarn-support, for transmitting pivotal movement to the yarn support from said mass to cause the tension on the yarn to decrease as the wound mass increases in diameter.

In the drawing,

Fig. 1 is a side elevation of a known form of winding machine made to embody the invention;

Fig. 2 is a plan of the tension means and other parts shown in Fig. 1;

Fig. 3 is a vertical sectional view of the preferred form of the yarn support and pressure means detached from the structure in which the yarn-support is mounted;

Fig. 4 is a similar but fragmentary view of what is shown in Fig. 3 on a larger scale.

The winding machine shown, embodying frame 1, the spindle 2 therein rotated at constant speed and on which the windings of yarn 3 (drawn from any suitable supply, not shown) are formed into a wound mass 4 having a taper, the lever-like element 5 fulcrumed at 5a in the frame and having a traversing yarn-guide 6 held bearing against said mass by a counter-weight 7 on said element, the clutch-detent 1a, and an arm 8

laterally projecting therefrom and affording a yarn-guide at 8a, is of well known construction.

Projecting from the frame and forming therewith a part of the supporting structure is a fixture 9 having a U-shaped terminus arranged in a vertical plane and provided with an extension 10 projecting from the lower arm of its U and equipped with an annular yarn-guide 11 of ample diameter. In effect a fixed extension of this fixture is a U-shaped bracket 12, arranged in a vertical plane and attached to the fixture at 12a. The arms of the U of this bracket receive a spindle 13 arranged in a vertical plane but so as to stand inclined inwardly and upwardly, the spindle being preferably screwed into the upper arm which terminates in a transverse yarn-guide 14.

The mentioned yarn-support here includes, with a metal block 15 having a back-rib 16 penetrated by the spindle, disks 15a freely rotative on studs 17 projecting one above the other from the block. All that is here broadly material is that the yarn-support affords, as by the outer faces of each of what are here shown as elements 15a distinct from the block, a yarn-supporting surface. The yarn-support may tilt on the spindle, or turn thereon from the position shown in Figs. 1 and 2.

Opposed to the outer face of each disk 15a and confined in opposing relation thereto by a stud 17 is the mentioned pressure means, here a gravity-actuated disk 18, which may also be rotative on the stud.

A preferred form of the yarn-support and pressure means is shown by Figs. 3 and 4. The block 15 has in its front face two circular recesses 19, one above the other, and a stud 20 upstanding centrally from each recess and preferably equipped with a freely revoluble bushing 21, there being a soft (as felt) washer 22 resting against the bottom and central of the recess. Coaxial with each stud is a freely revoluble concentrically corrugated disk 23 corresponding to disk 15a. Opposed to this disk and corresponding to disk 18 is a freely revoluble pressure disk generally indicated in Fig. 3 by character 24 and shown more clearly in Fig. 4 as comprising a concentrically corrugated disk-like element 24a, the corrugations of the latter being formed to mesh with those of disk 23.

If the disks are rotative they will be progressively rotated by the travelling yarn so as to avoid the latter grooving them by friction; the purpose in forming disks 23 and 24a with intermeshing corrugations is to enhance and steady their grip on the yarn.

Projecting from the front face of the block at its lower end is a post or guide 25. The yarn extends from its supply through guide 11 and between each yarn-supporting surface of the yarn-support and the corresponding pressure means and then over and under, respectively, the guides 14 and 8a to yarn-guide 6, extending in alternation past the opposite sides of post 25 and the two studs 17 or porcelain-bushed studs 20, as shown, all of which studs serve as yarn-guides. Thus the yarn is confined, while travelling, between the yarn-support and each pressure means. Fulcrumed between its ends on fixture 9 is a lever 26. One arm thereof is connected by a link 27 with a lug 15b of the yarn-support, eccentric with respect to spindle 13, and the other arm is connected by a link 28 with the element 5, this link being engageable in any of a series of notches 29 of said element, in which it is removably held by a clip 30.

Operation: Gravity active on each pressure means when the yarn-support is in the position shown is causing said means to exert a certain degree of pressure on the yarn. If the yarn-support be tilted from that position such pressure will obviously decrease, again increasing when the yarn-support is returned to the position shown.

When the yarn is being formed into a wound mass and it is desired, for instance and as usual, to provide for a decrease of tension on the yarn as said mass grows in diameter the means 6—5—28—26—27 serves to change the position of the yarn-support, specifically here to tilt it so that the pressure of the pressure means against 35 and consequently the tension on the yarn is gradually decreased.

Having thus fully described my invention what I claim is:

1. The herein-described mechanism for tension-

ing lengthwise travelling yarn including, with supporting structure, a yarn-support pivotally movable thereon, and pressure means normally urged and confined to the support to move in a straight line extending through, and crossing the pivoting axis of, such support and coactive with the latter to grip the portion of the yarn extending between them, said mechanism having yarn guiding means offset from each other lengthwise of said axis and maintaining the yarn between 10 said support and pressure means.

2. The herein-described mechanism for tensioning lengthwise travelling yarn including, with supporting structure, a yarn-support pivotally movable thereon, and pressure devices each normally urged to move in a straight line extending through, and crossing the pivoting axis of, such support and coactive with the latter to grip the yarn, said mechanism having yarn guiding means offset from each other lengthwise of said axis and 20 maintaining the yarn between said support and devices and also confining the latter to said support.

3. The herein-described mechanism for tensioning lengthwise travelling yarn including, with supporting structure, a yarn-support pivotally movable thereon, and pressure means normally urged and confined to the support to move in a straight line extending through, and crossing the pivoting axis of, such support and coactive with the latter to grip the portion of the yarn extending between them, said mechanism having yarn guiding means offset from each other lengthwise of said axis and maintaining the yarn between said support and pressure means, and 30 one of which is at the output side of the pressure means and has a yarn contact surface extending transversely to said axis.

FREDERICK KLEIN.
